UNITED STATES PATENT OFFICE.

HUGO NEUMAN, OF DETROIT, MICHIGAN, ASSIGNOR TO DIAMOND MANUFACTURING COMPANY, OF DETROIT, MICHIGAN, A CORPORATION OF MICHIGAN.

METHOD OF SHAPING METAL.

1,091,381.

Specification of Letters Patent. Patented Mar. 24, 1914.

Application filed January 27, 1912. Serial No. 673,923.

To all whom it may concern:

Be it known that I, HUGO NEUMAN, a citizen of the United States of America, residing at Detroit, in the county of Wayne and 5 State of Michigan, have invented certain new and useful Improvements in Methods of Shaping Metal, of which the following is a specification, reference being had therein to the accompanying drawings.

10 My invention relates to a new and improved method for shaping metal, and more particularly to a method for progressively shaping a flat strip or ribbon into channeled form.

15 The invention resides in the novel operations as more fully hereinafter described and particularly pointed out in the claims.

In the drawings, Figure 1 represents a side elevation of the machine in which my 20 improved method is carried out; Figs. 2, 3 and 4 are end elevations of the several pairs of forming rolls; Figs. 5 to 9 inclusive are elevations of the several dies; Fig. 10 is a 25 perspective view illustrating certain details; Fig. 12 is an elevation of a channeled strip formed by my improved method; and Figs. 13 to 16 inclusive illustrate different stages 30 of the metal strip during the shaping thereof to the cross-section shown by Fig. 12.

I will describe my improved method in connection with the forming of a channel shaped strip A (see Fig. 12), which is designed as a resilient bearing for the edge of 35 a glass panel. This strip has the side edges o thereof rebent to provide inwardly extending portions o' spaced from the sides, while the latter and the bottom p of the channel are slightly grooved, as indicated by the 40 reference-letters q r; also, the bottom is tempered, though the sides are not.

With my improved method the member A is formed from a flat strip, the sides being 45 progressively shaped and the base of the channeled product also progressively tempered. Preferably the progressive tempering and shaping are simultaneously effected and the final tempering completed during the channelling operation.

50 For carrying out my novel method I desire to employ the machine illustrated in the drawings, in which—
B designates the bed of the machine.

D E, D' E' and D² E² are pairs of forming rolls mounted upon shafts journaled in 55 the bed, the shafts being positively and continuously driven at a uniform speed and the shafts of one roller of each set being yieldably pressed toward the other by springs E⁵.

P is a straightening and beading die arranged intermediate the first two sets of rolls and Q designates a finishing die.

The flat ribbon is fed from the reel (not shown) over a guide roll O' to the rolls D E. The roll D has formed in the face thereof of grooves a³ b³ and c³, while the roll E has complementary projections d³ e³ and f³, the portions a³ and d³ being in yieldable contact but the complementary remaining portions being slightly spaced. The circumference 70 of the roll D is greater than its coöperating roll, and as the shafts upon which the rolls are fixed are driven at a uniform speed the forming surfaces of the rolls will be driven at different speeds. Therefore, as the strip 75 passes between the members D E, the difference in speed between the portions a³ d³ will tend to slightly lengthen the middle of the strip. This lengthening is substantially taken care of by a slight lateral flowing of 80 the metal between the portions a³ d³.

The portions b³ e³ and c³ f³ coöperate to bend the sides, the strip as it enters the die P having the form shown in Fig. 13. The die P at its forward end has substantially 85 the same cross-section as that of the strip when it leaves the rolls D E, but the cross-section of this die gradually tapers to the form shown by Fig. 5, serving to roll the edges of the strip inward, and also correcting any distortion of the strip, giving the latter the contour of Fig. 14. In passing through the rolls D' E' the edges are rolled slightly farther, the members D' E' having 90 coöperating grooves g³ h³ adjacent the sides 95 of their faces for effecting this operation. At the center, however, the coöperating surfaces are the same as the central portion of the rolls D E, and as with the latter set of rolls the central portions are the only parts 100 of the working faces of the rolls D' E' that are in engagement. Also, the circumference of the roll D' is greater than that of the roll E', producing a further tempering of the central portion of the strip. As the strip 105 enters the rolls D² E², it has the configura-

tion shown by Fig. 15, and in passing through the forming rolls D^2 E^2 the strip is channeled and the tempering completed. Thus, the face of the roll E^2 is grooved or 5 channeled at i^3 , the bottom j^3 of the groove having the same shape as the projection d^3 on the roll E , that is the configuration of the bottom p of the finished product, while the sides of the groove are diverged. 10 k^3 is a projection on the roll D^2 , having a face l^3 of a contour complementary to the portion j^3 of the member E^2 , but the sides of this projection are straight and spaced a sufficient distance from the diverging sides 15 of the complementary roll to permit the beaded ends of the strip to pass therethrough. The variation of the circumference between the rolls D^2 E^2 is greater than between the first two sets of rolls, and the 20 pressure applied to the roll E^2 by the spring E^5 therefore is considerably greater than the pressure applied to the roll E^1 . As the strip passes through these latter rolls, the tempering of the base of the channel is completed. 25 The strip as it is fed to the die Q has the configuration shown by Fig. 16. This die comprises a plurality of spaced forming members Q' Q^2 Q^3 and Q^4 , through which passes a mandrel Q^5 . The forming apertures of these parts gradually increase in 30 size from the member Q' to Q^4 (see Figs. 6 to 9 inclusive), and the apertured portion of each member tapers in cross section from the entrance to the exit side thereof, as will 35 be seen upon reference to Fig. 11. The mandrel g^5 is slightly tapered longitudinally from its forward end, while the bottom and sides are slightly concaved to fit the bottom and sides of the channel strip. In passing 40 through the die Q , the form of the member is progressively changed from that shown in Fig. 16 to that of the finished article. 45 In metal bending machines where the article is of comparatively small cross-section, a slight variation in the thickness of the metal is quite frequently highly objectionable. The fact that the thickness of the metal strip differs slightly is of little importance in the initial steps of shaping the strip, 50 but as the opening in the finishing die is more or less restricted a very slight unevenness in the metal passing therethrough tends to give the latter an uneven or varying cross-section and also produces a drawing of the 55 sides. To overcome this objection, I have arranged the mandrel within the members Q' Q^2 Q^3 Q^4 , so that it will be free to move, within certain limits, in relation to the forming apertures thereof. As shown, the mandrel is provided with a vertical projection n^8 which is arranged within a slot o^8 in the member Q' and has the forward end thereof positioned to abut against the member Q^2 , the forward movement of the mandrel being 60 thereby limited. The portion of the mandrel 65

which passes through the forming apertures is of a size sufficiently smaller than the latter to adjust laterally or vertically, so as to compensate for any uneven thickness in the strip. 70

What I claim as my invention is:

1. The method of forming channel strips from a flat ribbon of metal, which consists in progressively shaping a portion of the cross-section of the ribbon without tempering the same, and in tempering another portion of the cross-section of the ribbon during said progressive shaping. 75

2. The method of forming channel strips from a flat ribbon of metal, which consists in progressively shaping the sides of the ribbon and tempering the central portion during the shaping of the sides. 80

3. The method of forming channel strips from a flat ribbon of metal, which consists in progressively shaping the sides of the ribbon and shaping and tempering the portion of the ribbon forming the base, simultaneously. 85

4. The method of forming channel strips from a flat ribbon of metal, which consists in progressively shaping the sides without tempering the same, and progressively tempering and shaping the central portion of the ribbon simultaneously. 90

5. The method of forming channel strips from a flat ribbon of metal, which consists in progressively shaping the sides of the ribbon, and progressively tempering the central portion. 95

6. The method of forming channel strips from a flat ribbon of metal, which consists in progressively shaping the sides and in passing the ribbon during the shaping of the sides, between surfaces having a difference in speed to temper the portion of the ribbon which forms the base of the channel strip. 100

7. The method of forming channel strips from a flat ribbon of metal, which consists in passing the ribbon between a plurality of surfaces having a difference in speed to progressively shape and temper the ribbon. 110

8. The method of forming channel strips from a flat ribbon of metal, which consists in passing the ribbon between a plurality of pairs of rolls and dies to progressively shape the sides and progressively temper the base, the final tempering being effected during the channeling operation. 115

9. The method of forming channel strips from a flat ribbon of metal, which consists in partially shaping the sides of the ribbon, simultaneously partially tempering the central portion of the ribbon and partially beading the sides, in continuing the tempering of the central portion of the ribbon, and simultaneously shaping the sides, in channeling the ribbon, and in completing the tempering of the sides during the channel- 125 130

ing operation and in then finishing the shaping of the sides.

10. The method of forming channel strips from a flat ribbon of metal, which consists in passing the flat ribbon through a pair of forming rolls to partially shape the sides of the ribbon and partially temper the central portion, in passing the ribbon through a straightening and beading die, then continuing the tempering of the central portion and the shaping of the sides by another set of rolls, then passing the ribbon through a pair of rolls to channel the same and complete the tempering of the central portion 15 of the ribbon, and in finishing the shaping of the sides by dies without drawing the metal.

11. The method of forming channel strips from a flat ribbon of metal, which consists 20 in progressively shaping and beading the

sides, in channeling the strip, and in then completing the shaping of the sides.

12. The method of forming channel strips from a flat ribbon of metal, which consists in passing the flat ribbon through a pair of 25 forming rolls to partially shape the sides of the ribbon, in passing the ribbon through a straightening and beading die, in continuing the shaping of the sides of the strip by another set of rolls, then passing the ribbon through a pair of rolls to channel the same, and in finishing the shaping of the sides by 30 passing the strip through stationary dies provided with a shaping mandrel.

In testimony whereof I affix my signature 35
in presence of two witnesses.
